UNITED STATES PATENT OFFICE.

ALWIN F. KOEHLER, OF JOPLIN, MISSOURI.

MORTAR AND CONCRETE MIXING MACHINE.

No. 820,580.

Specification of Letters Patent.

Patented May 15, 1906.

Application filed September 11, 1905. Serial No. 277,932.

To all whom it may concern:

Be it known that I, ALWIN F. KOEHLER, of the city of Joplin, county of Jasper, and State of Missouri, have invented a new and useful 5 Mortar and Concrete Mixing Machine, of which the following is a specification.

My invention relates to a machine for mixing mortar or concrete, first mixing dry, then, when the ingredients are thoroughly mixed, 10 adding sufficient water to bring the mass to proper consistency for use.

Reference is to be had to the accompanying drawing, which forms a part of this specification.

15 The drawing is a sectional view longitudinally and vertically through the center of the machine.

In the drawing, A represents a hopper into which the materials to be mixed are placed 20 and which converges at the bottom, entering the contracted end of the cylinder B.

B is the mixing barrel or cylinder, which is held in position and revolved by the spider-arms C, fastened to B at one end and to hubs 25 D at the other end. Hubs D are in turn fastened to shaft E. This shaft E, which is hollow, rests within the journals F F on the framework G and is closed at one end. The 30 other end is fitted with a stuffing-box H, which makes connection between the shaft and the water-supply pipe I.

As shown in the drawing, motion is imparted to shaft E and thence to cylinder B through the gear J, pinion K, shaft L, and 35 pulley M. Shaft E for a portion of its length within the cylinder has a number of small holes N, drilled from the outside into the space within.

The method of operation is as follows: The 40 machine is first set with the hopper end slightly elevated, so that the material being mixed will travel toward and out at the other end. Water is admitted to interior of shaft E through the pipe I and stuffing-box H, and

power being applied to pulley M a revolving 45 movement is given the mixing-cylinder. The materials to be mixed are now thrown into the hopper A, which conducts them into the contracted end of cylinder B. The movement of this cylinder carries the materials 50 part of the way up at one side as the cylinder revolves, whence they fall back upon the bottom, and since the cylinder is set in an inclined position they work toward the lower end. Soon they reach a position where they 55 come within range of the spray of water discharged through the holes N in the hollow shaft E, which completes the operation, delivering the mortar at the discharge end ready 60 for use.

Having thus fully described my invention, what I desire to secure by Letters Patent is—

A concrete-mixing machine comprising the combination of a stationary hopper; a cylinder provided at its front end with a top 65 formed with a hole into which fits the lower end of said hopper; the rear end of said cylinder being entirely open for the discharge of the material; a supporting-frame; a tubular shaft journaled in said frame and having its 70 rear end closed and its front end provided with a gasket, the front half of said shaft within said cylinder being imperforate while the rear half thereof within said cylinder is perforated; a water-supply pipe which fits 75 into said gasket; driving mechanism for rotating said shaft; and spiders fast to said shaft and the inside of said cylinder, the openings between the arms of said spiders permitting the free discharge of the material 80 therethrough.

Signed at Joplin, in the county of Jasper and State of Missouri, this 7th day of September, 1905.

ALWIN F. KOEHLER.
